UNITED STATES PATENT OFFICE.

HARRY W. HAMILTON, OF INDIANAPOLIS, INDIANA, ASSIGNOR TO THE HAM-MEIX MANUFACTURING COMPANY, OF INDIANAPOLIS, INDIANA, A CORPORATION OF INDIANA.

STARTER FOR INTERNAL-COMBUSTION ENGINES.

1,149,135.

Specification of Letters Patent. Patented Aug. 3, 1915.

Application filed June 16, 1913. Serial No. 773,873.

To all whom it may concern:

Be it known that I, HARRY W. HAMILTON, a citizen of the United States, residing at Indianapolis, in the county of Marion and State of Indiana, have invented a new and useful Starter for Internal-Combustion Engines, of which the following is a specification.

It is the object of my invention to provide a simple and positive starter for internal combustion engines, which will act uniformly and without violence on the engine, requires the expenditure of a minimum amount of energy, is easily and inexpensively maintained, and is fool-proof. In attaining this object, I provide a gas storage reservoir for holding gas under pressure, and supply gas from this reservoir through a control valve to start the engine by direct fluid pressure, either by supplying the gas under pressure to the engine itself, preferably through a distributor if the engine is a multicylinder engine, or by supplying it to a suitable auxiliary or starting motor, which may be connected to the engine by an automatic clutch acting to transmit power only from the auxiliary motor to the engine. Under normal conditions, the pressure in the gas storage reservoir is restored mechanically by the subsequent engine operation, such restoring action ceasing automatically when a predetermined pressure in the reservoir is reached. However, when the demands on the gas reservoir are sufficient to reduce the pressure therein below a second and lower predetermined value, as when there is difficulty in getting the engine to operate under its own power, the pressure in such reservoir is automatically maintained otherwise, as by the generation of gas, conveniently in the reservoir itself, to maintain such pressure at an effective value. This gas generation, which is conveniently of carbon dioxid, is automatically controlled so as to maintain the gas pressure in the reservoir at a substantially constant predetermined value within certain narrow limits, and to replenish the pressure to a value which is constant within even narrower limits, and yet to protect against excessive rises in pressure from "over-generation." In order to guard against waste and inefficiency, the gas reservoir may be automatically cut off from the engine whenever

the gas pressure falls below a third and still lower predetermined value, thus giving the gas generator time to build up a pressure high enough for efficiency. With the generator shown, this time is ordinarily but a few seconds. In order to facilitate the starting operation, the compression within the engine cylinder or cylinders may be relieved, at least when they are on their compression strokes.

The accompanying drawing illustrates my invention.

In this drawing, Figure 1 is a semi-diagrammatic view showing the system in its entirety and some of the parts in structural detail, the normal mechanical maintenance of the pressure in the gas reservoir being produced by having one of the engine cylinders connected thereto through a suitable check valve; Fig. 2 is a section through the distributor on the line 2—2 of Fig. 1; Fig. 3 is another semi-diagrammatic view showing a modification in which an auxiliary or starting motor is used; and Fig. 4 is a fragmentary view showing a modification in which the gas pressure is normally maintained by a separate pump operated by the engine.

The gas generator comprises a gas-generating tank 10, which is conveniently also the gas storage reservoir, in which a quantity of soda or soda solution 11 or other suitable substance, solid or liquid, is placed, and a liquid tank 12 for supplying dilute sulfuric acid or other reagent to the gas tank 10 to react with the soda or other substance in the latter to produce carbon dioxid or other gas. For example, calcium carbid and water may be used as the reagents in place of soda and sulfuric acid, in which case the gas produced is acetylene; but I now deem carbon dioxid gas preferable. The liquid tank 12 is usually considerably smaller than the gas tank 10, and the latter may be many times smaller than the tanks ordinarily used in connection with starters operating by direct fluid pressure. The two tanks 10 and 12 are connected by a pipe 13 leading from the top of the gas tank 10 and conveniently provided with a hand shut off valve 14, a pipe 15 leading from the bottom of the liquid tank 12, and a pressure governor for controlling the pressure above the liquid in the tank 12. This governor comprises a diaphragm 19

clamped between two casing sections 20 and 21, a smaller diaphragm 22 clamped between the casing section 20 and a third casing section 23, a valve stem 24 which passes through the diaphragm 22 and is clamped thereto by clamping nuts 25 and is provided with a head 26 which bears against that side of the diaphragm 19 which is toward the casing section 20, and an adjustable spring 27 which holds said head 26 against the diaphragm 19 and thus determines the pressure at which the pressure governor operates. The pipes 13 and 15 lead into the casing section 23 on the side of the diaphragm 22 remote from the diaphragm 19, the needle point on the valve stem 24 engaging its valve seat on the casing section 23 when the diaphragm 19 is moved against the action of the spring 27. This movement of the diaphragm 19 is obtained by connecting the casing section 21 with the top of the tank 10, as by means of a pipe 28 in which may be located a hand shut off valve 29. The purpose of the diaphragm 22 is to prevent the pressure in the tank 10 from acting against the side of the diaphragm 19 which is toward the casing section 20, said latter casing section being either closed or provided with vent openings 30.

The tank 10 is provided with a removable head 31 at one end, or at each end if desired, this head 31 being held by swinging bolts 31' to a ring 32 brazed or otherwise firmly attached to the body of the tank. The ring 32 and head 31 preferably fit together by interfitting ridges and grooves, as illustrated, to assist in making the joint gas-tight, suitable gaskets being provided where necessary. By removing the head or heads 31, the tank may easily be cleaned out when desired. A removable screw plug 33 fits into a hole in the head 31, an inwardly opening check valve 34 being screwed into the inner end of this opening. By removing the plug 33 an initial charge of the same reagent as in the tank 12 may be introduced into the tank 10 by means of a suitable syringe projected into the opening, if it is desired to produce the initial pressure in the tank 10 by chemically generated gas. The check valve 34 prevents the gas which is immediately generated from escaping before the plug 33 can be replaced.

When gas is drawn from the tank 10, and the pressure in said tank falls below a predetermined value, the gas pressure above the liquid in the tank 12 forces the latter through the pipe 15, the pressure governor, and the pipe 13 into the gas tank 10. This liquid reacts with the soda in the latter tank, and produces more gas, the pressure of which forces the liquid still in the pipes 13 and 15 back into the tank 12, gas from the tank 10 bubbling through the liquid in the tank 12

to maintain, or replenish, the pressure above such liquid. When the pressure reaches a predetermined value in the tank 10, the diaphragm 19 is moved by such pressure against the spring 27 to bring the point of the valve stem 24 into engagement with its valve seat, thus shutting off the connection between the two tanks 10 and 12 and preventing the gas pressure above the liquid into the tank 12 from exceeding a predetermined value. As the capacity of the pipes 13 and 15 is comparatively small, the value of the pressure above the liquid in the tank 12 is thus maintained substantially constant, regardless of the quantity of the liquid withdrawn, and "over-generation" due to the successive building up of the pressure above the liquid in the tank 12 is effectually prevented.

While the gas produced in the tank 10 may be used for many purposes, I use it in accordance with the present invention as an auxiliary for starting an internal combustion engine, as of an automobile, by direct pneumatic pressure. To this end, gas from the tank 10 is supplied through a pipe 35, which is preferably a branch pipe from the pipe 28 so that it may be controlled in common with the latter pipe by the hand shut off valve 29, and an automatic cut off valve to a supply pipe 36 leading to the engine through a hand control valve and, in the arrangement shown in Fig. 1, a distributor, of which more hereafter. This automatic cut off valve comprises casing sections 20' and 21', diaphragms 19' and 22', lock nuts 25', a head 26', and a spring 27' identical in structure with the parts 20, 21, 19, 22, 25, 26, and 27 already described. The valve stem 24' of the automatic cut off valve differs from the valve stem 24 of the pressure governor in that it has a flaring conical end 37 instead of a needle point, said flaring end co-operating with a valve seat on a casing section 23' substantially identical with the casing section 23 save that the valve seat is on the side of the casing remote from the diaphragms. The pipes 35 and 36 are connected to the casing section 23' in substantially the same manner as are the pipes 13 and 15 to the casing section 23 of the pressure governor. The automatic cut off valve operates, in a manner exactly the reverse of that of the pressure governor, to close the connection between the gas tank 10 and the pipe 36 when the pressure in such tank falls below a predetermined value. This predetermined value is lower than that at which the pressure governor causes the opening of its valve. This action of the automatic cut off valve prevents the operator from wasting the gas by continuing to draw it from the tank 10 when the pressure therein is too low to be efficient for starting the engine, and allows the generator time, only a few seconds ordinarily being necessary, to build

up the pressure to an efficient value; then the automatic cut off valve opens and allows gas to be drawn from the tank to continue the starting operation.

5 The pipe 36 leads to the casing 40 of the control valve. This casing has a central passage 41 provided at its two ends with outwardly and oppositely facing valve seats, with which valve heads 42 and 43, which are 10 mounted on a common valve stem 44 smaller than the passage 41 and are spaced farther apart than are the valve seats, respectively coöperate. The valve head 42 and its valve seat are conical, while the valve head 43 and its seat may be flat, the valve head 43 preferably being faced with rubber 45 or other yieldable material on its side toward the valve seat. The valve stem 44 of the control valve is suitably connected, as by a 20 bell-crank lever 46, to be moved by a rod 47 and push knob 48, the latter conveniently being mounted on the dash board of an automobile if the apparatus is used in connection with an automobile. The control 25 valve is biased, both by a spring 49 and by the pressure from the pipe 36 on the valve head 42, to hold said valve head against its seat and thus close the valve. When the knob 48 is pushed, the valve is opened by 30 the separation of the valve head 42 from its seat, the valve head 43 at the same time being moved against its valve seat to prevent leakage around the valve stem. The opening 35 of the control valve opens the pipe 36 to a pipe 50, leading from the passage 41 between the two valve seats.

In the arrangement shown in Fig. 1, the pipe 50 leads to an opening 51 on one side of the casing 52 of the distributor, the other 40 side of said casing being provided with a series of openings, 53 equidistant from the center of the casing and equally spaced apart, the number of said openings 53 being equal to the number of cylinders of the engine 45 with which the device is associated, a four cylinder engine being illustrated. The openings 53 are connected by pipes 54 to valves 55 opening into the respective engine cylinders 1, 2, 3, and 4, said valves 55 being 50 normally closed and being operable by the rod 47 when the latter is moved to open the control valve. The valves 55 may be substantially the same in structure as the control valve, but here the gas pressure is admitted through the opening at the side of the valve casing and discharged through the opening at the end thereof, whereas in the control valve the gas is admitted through the opening at the end of the valve casing 55 and discharged through the opening at the side thereof. Thus in each valve 55, all pressure from the gas tank 10 being cut off when the control valve is closed, any pressure from the associated engine cylinder 60 acts at all times against the head of the 65 valve, thereby aiding the spring in keeping the valve seated and preventing leakage when the starter is not being operated to start the motor. If desired, a shut off valve 29', separate from the valve 29, may be 70 placed in the pipe 36, conveniently being located on the dashboard if the device is used on an automobile. The casing 52 of the distributor is also provided with an opening 56 on the same side of the casing as but 75 nearer the center thereof than are the openings 53, said opening 56 communicating, as by a conduit 57, with the atmosphere.

Mounted within the casing 52 is a rotary disk 60, which is driven at a speed proportional to that of the engine shaft 59, conveniently at one-half engine speed if the engine is of the four-cycle type. The disk 60 is thinner than the space within the casing 52, and when pressure is admitted through the pipe 50 and opening 51 is held firmly against that side of the casing which is provided with the openings 53 and 56. When such pressure is relieved, the disk moves slightly away from the inner surface of the 90 casing, and its center on the side of the disk toward the opening 51 bears against a bearing bell 61, thus reducing friction to a minimum. The disk 60 is provided with a notch 62 in its periphery, such notch being of such 95 angular length that it successively opens the various openings 53 to the space on the other side of such disk and thus to the pipe 50 during the time that the corresponding engine cylinders are on their explosion strokes, 100 but closes the openings 53 before the exhausts of such respective cylinders are opened. The disk 60 is provided on its side toward the openings 53 and 56 with a circular recess 63 which is provided with a 105 sectoral wing 64. The circular recess continually covers the opening 56 during the rotation of the disk 60, and the wing 64 of such recess covers the various openings 53 successively. The wing 64 of this recess is 110 so located that it opens the various engine cylinders to the atmosphere, through the openings 53 and 56, when such cylinders are on their compression strokes. This eliminates, or greatly reduces, the compressing action within the cylinders, and thus 115 greatly diminishes the work required in starting the engine. While permissible, it is not necessary that the wing 64 of the recess open the engine cylinders to the atmosphere during the whole of their compression strokes, as ample relief is found to be obtained by connecting such cylinders to the atmosphere during the latter parts of such 120 strokes.

In order to make the chemical generation of gas to maintain, or replenish, the pressure in the tank 10 a mere auxiliary action, and thus to produce economy in chemicals, I provide other means for normally maintain- 130

ing the gas pressure in said tank above the predetermined value at which the liquid in tank 12 is admitted to the tank 10. In the arrangement shown in Fig. 1, this consists of a pipe 70 connecting the tank 10 and the engine cylinder 1, in which pipe 70, conveniently at the cylinder end thereof, is a check valve 71 which admits the passage of gas only from the cylinder to the tank, and even that only in case the pressure in the tank is below a predetermined value. This predetermined value is somewhat higher than that at which the pressure governor causes its valve to open. The check valve 71 may take various forms, but in the form illustrated comprises a body portion 72 provided with external heat-radiating ribs 73 and with a central longitudinal opening 72' enlarged at the middle and smaller at the bottom and having a valve seat 74 between said middle and bottom portions, and a valve stem 75 movable in said opening and guided by the upper portion thereof and cooperating with said valve seat 74 to open and close the valve. The lower end of the opening in the valve body is connected to the cylinder 1 and the middle portion of such opening to the tank 10 through the pipe 70. The valve stem 75 is provided with an opening 76 connecting the middle enlarged portion of the opening 72' with that portion of said opening which is above the valve stem, so that the pressure from the tank 10 may act upon the top of the valve stem to assist in holding the valve closed.

With this arrangement the operation of the engine causes the explosions in cylinder 1 to force part of the burned gases produced by such explosions through the check valve 71 and the pipe 70 into the tank 10 whenever the pressure in said tank is below the predetermined value at which the check valve 71 may open. When the pressure in said tank equals or exceeds that value, the check valve 71 remains constantly closed.

Instead of using the burned gases from one of the engine cylinders for replenishing the gas tank 10, such replenishing may be obtained by a pump 78 driven from the engine shaft 59, as shown in Fig. 4; a clutch 78' may be included in the mechanical connection between the engine shaft 59 and the pump 78. Conveniently this pump 78 supplies air to the tank 10, though any other desired gas may be supplied. The connection from the pump 78 to the tank 10 is through a pipe 70', in which may be located a suitable check valve 79. When a predetermined pressure is reached in the tank 10, the reaction of such pressure on the pump causes the supply of gas from the latter to the tank to cease, or the clutch 78' may be disengaged.

To start the engine, the ignition circuit, if desired, first being closed as is usually

done preparatory to cranking the engine, the knob 48 is pushed to open the control valve and the valves 55. This admits pressure from the tank 10, provided such pressure is sufficiently high to allow the automatic cut off valve to be open, through the opening 51 of the distributor, the notch 62, and the proper opening 53 and pipe 54, into that engine cylinder which is on its explosion stroke. At the same time, the pressure within the engine cylinder which is on its compression stroke is relieved through the recess 63 and its wing 64, cooperating with the opening 56 and pipe 57. The pressure thus supplied from the tank 10 to the cylinder on its explosion stroke operates the piston within said cylinder to move the engine forward, the disk 60 being rotated with the engine at proper relative speed. As the disk 60 is rotated, gas from the tank 10 is admitted under pressure to the engine cylinders in proper succession on their explosion strokes, the compression in each of said cylinders being previously relieved, if desired, to diminish the work required. After a few revolutions of the engine shaft, the knob 48 may be released to permit the spring 49 to close the valves 55 and the control valve. The ignition circuit must now be closed if it has not previously been closed. The engine is now in its normal condition and operates under its own power; the momentum given it by the starting carrying it past the point where the first explosion of compressed carbureted air takes place, just as in the case of cranking by hand. While the starter gas I preferably use is carbon dioxid, which is not explosive, and even if admitted to the firing chamber of the cylinder or cylinders of the engines at the time the ignition sparking takes place therein would not produce an explosion in the firing chamber or in the exhaust pipe or muffler, by my device the starter gas is not admitted to any cylinder while ignition sparking takes place therein; that is, it is not admitted by the distributor into any cylinder until after the piston on its firing stroke has passed its ignition point and is on its downward stroke, and it is exhausted or withdrawn from the cylinder by the succeeding exhaust stroke of the engine and before the next compression stroke and consequently before the next succeeding ignition spark takes place in such cylinder, the operation being the same in each separate cylinder of the engine.

As soon as the engine begins to operate under its own power, it begins to replenish the gas pressure within the tank 10, either by the burned gases from the cylinder 1 supplied through the check valve 71 and the pipe 70 or by the pumping action of the pump 78. This replenishing continues until the pressure in the tank has returned to its

normal predetermined maximum value. Under ordinary conditions, that is, when the engine starts under its own power with reasonable quickness, the amount of gas drawn from the tank 10 is not sufficient to reduce the pressure in said tank below the predetermined value at which the pressure governor opens its valve, so that the gas pressure in the tank 10 is normally maintained at an efficient value by the replenishing action of the engine operation. However, when the engine starts with difficulty and an unusually large amount of gas is drawn from the tank 10 to produce such starting, the pressure in said tank falls sufficiently low to cause the opening of the valve of the pressure governor and the passage of liquid from the tank 12 to the tank 10, which liquid reacts with the substance in said tank 10 to regenerate the gas pressure chemically. Thus the chemical generation of the gas is an ever ready auxiliary operation which takes place whenever it is demanded. If, for any reason, as because the engine persistently fails to begin operating under its own power and repeated efforts to start it are required, so much gas is drawn from the tank 10 that the pressure therein is reduced below the pressure required for the opening 30 of the valve of the pressure governor and to a lower predetermined value, the automatic cut off valve is closed to give such pressure time to build up by the chemical regeneration. As soon as the pressure is built up above this lowest predetermined value, which building up as heretofore shown is practically an instantaneous operation, the automatic cut-off valve opens to allow the starting operation to continue.

If desired, the initial creation of pressure in the tank 10 may be by the engine operation instead of by the injection of a charge of the liquid reagent through the valve 34.

In the arrangement shown in Fig. 3, the starter gas from the tank 10 is not supplied directly to the engine cylinders to start the engine, but instead the distributer discharging to the engine cylinders is omitted, and the discharge side of the control valve is connected by a pipe 80 to an auxiliary or starting motor 81. This motor 81 may be of any desired type, but is conveniently a rotary motor, as shown; and it is conveniently mechanically connected to the shaft of the engine by a roller clutch 82, which transmits power from the motor 81 to the engine to start the latter, but not from the engine to the motor 81, thus allowing the latter to be at rest under normal conditions. With the arrangement using the auxiliary or starting motor, the valves 55 discharge to the atmosphere or may be dispensed with entirely; and may if desired take the form of ordinary pet cocks in either arrangement.

Although my system comprises a number

of moving parts, these parts are all so arranged that no packings are required at any moving joints. As a result, the difficulties caused by such packings are entirely eliminated.

70

I claim as my invention:

1. In combination, an internal combustion engine, a gas generator in which the production of gas is controlled by the pressure of the gas in the generator, such generator comprising two connected compartments respectively containing a liquid and another substance which react to produce the gas, a control valve for supplying gas from said generator to start said engine, and means whereby the engine operation replenishes the gas pressure.

75

2. In combination, an internal combustion engine, a gas generator in which the production of gas is controlled by the pressure of the gas in the generator, a control valve for supplying gas from said generator to start said engine, and means whereby the engine operation replenishes the gas pressure.

80

3. In combination, an internal combustion engine, a gas generator in which the production of gas is controlled by the pressure of the gas in the generator, a control valve for supplying gas from said generator to start said engine, means whereby the engine operation replenishes the gas pressure, and an automatic cut off valve for closing the discharge from the generator when the gas pressure in the generator falls below a predetermined value.

95

4. In combination, a multi-cylinder internal combustion engine, a gas generator in which the production of gas is controlled by the pressure of the gas in the generator, a control valve for supplying gas from said generator to said engine, means whereby the engine operation replenishes the gas pressure, a distributer operated from the engine and directing the gas supplied from the gas generator to the various engine cylinders on their explosion strokes, a valve associated with each engine cylinder and controlling its connection to the distributer, and a common operating means for said last named valves and said control valve, said distributer being provided with ports for connecting the engine cylinders to the atmosphere when they are on their compression strokes and the associated valves are open.

100

5. In combination, a multi-cylinder internal combustion engine, a gas generator in which the production of gas is controlled by the pressure of the gas in the generator, a control valve for supplying gas from said generator to said engine, means whereby the engine operation replenishes the gas pressure, and a distributer operated from the engine and directing the gas supplied from the gas generator to the various engine cylinders on their explosion strokes, said dis-

105

- tributer being provided with ports for connecting the engine cylinders to the atmosphere when they are on their compressed strokes and the associated valves are open.
- 5 6. In combination, a multi-cylinder internal combustion engine, a gas generator in which the production of gas is controlled by the pressure of the gas in the generator, a control valve for supplying gas from said generator to said engine, means whereby the engine operation replenishes the gas pressure, a distributer operated from the engine and directing the gas supplied from the gas generator to the various engine cylinders on their explosion strokes, and a valve associated with each engine cylinder and controlling its connection to the distributer, said distributer being provided with ports for connecting the engine cylinders to the atmosphere when they are on their compression strokes and the associated valves are open.
- 10 7. In combination, a multi-cylinder internal combustion engine, a gas generator in which the production of gas is controlled by the pressure of the gas in the generator, a control valve for supplying gas from said generator to said engine, means whereby the engine operation replenishes the gas pressure, a distributer operated from the engine and directing the gas supplied from the gas generator to the various engine cylinders on their explosion strokes, a valve associated with each engine cylinder and controlling its connection to the distributer, and a common operating means for said last named valves and said control valve.
- 15 8. In combination, a multi-cylinder internal combustion engine, a gas generator in which the production of gas is controlled by the pressure of the gas in the generator, a control valve for supplying gas from said generator to said engine, means whereby the engine operation replenishes the gas pressure, a distributer operated from the engine and directing the gas supplied from the gas generator to the various engine cylinders on their explosion strokes, and a valve associated with each engine cylinder and controlling its connection to the distributer.
- 20 9. An improvement in the art of starting an internal combustion engine which consists in supplying gas under pressure to start the engine, replenishing the gas pressure by the subsequent operation of the engine, and chemically generating gas to replenish such pressure when the latter falls below a predetermined value lower than the value at which the engine operation normally maintains such pressure.
- 25 10. An improvement in the art of starting an internal combustion engine which consists in supplying gas under pressure to start the engine, replenishing the gas pressure by the subsequent operation of the engine, and generating gas independently of the engine to replenish such pressure when the latter falls below a predetermined value lower than the value at which the engine operation normally maintains such pressure.
- 30 11. An improvement in the art of starting an internal combustion engine which consists in supplying gas under pressure to start the engine, replenishing the gas pressure by the subsequent operation of the engine, and chemically generating gas to replenish such pressure when the latter falls below a predetermined value.
- 35 12. An improvement in the art of starting an internal combustion engine which consists in supplying gas under pressure to start the engine, replenishing the gas pressure by the subsequent operation of the engine, and generating gas independently of the engine to replenish such pressure when the latter falls below a predetermined value.
- 40 13. In combination, a multi-cylinder internal combustion engine, a gas generator in which the production of gas is controlled by the pressure of the gas in the generator, a control valve for supplying gas from said generator to said engine, means whereby the engine operation replenishes the gas pressure, and a distributer operated from the engine and directing the gas supplied from the gas generator to the various engine cylinders on their explosion strokes.
- 45 14. In witness whereof, I have hereunto set my hand at Indianapolis, Indiana, this 14th day of June, A. D. one thousand nine hundred and thirteen.
